COOKING RANGE

Daniel G. Meckley III, Mansfield, Ohio, assignor to The
Tappan Company, Mansfield, Ohio, a corporation of
Ohio

Filed Jan. 13, 1965, Ser. No. 83,406

Term of patent 14 years

(Cl. D81—4)

Fig. 1

FIG. 1 is an oblique perspective view of a cooking range embodying my new design;

FIG. 2 is a front elevation thereof;

FIG. 3 is a side elevation thereof as viewed from the right in FIG. 2;

FIG. 4 is a side elevation of said range as viewed from the left in FIG. 2;

FIG. 5 is a front elevation of a modified form thereof and differs from the embodiment of FIG. 2 only as to the appearance of the lower door formation apparent, the side elevations of the FIG. 5 embodiment being identical with those illustrated in reference to the FIG. 2 embodiment.

The rear of the cooking range, which is not shown, is conventionally plain.

I claim:

The ornamental design for a cooking range, as shown and described.
